(No Model.)

J. DAVIS.
MACHINE WRENCH.

No. 289,396.

Patented Dec. 4, 1883.

UNITED STATES PATENT OFFICE.

JOHN DAVIS, OF NEW BEDFORD, MASSACHUSETTS.

MACHINE-WRENCH.

SPECIFICATION forming part of Letters Patent No. 289,396, dated December 4, 1883.

Application filed February 8, 1883. (No model.)

To all whom it may concern:

Be it known that I, JOHN DAVIS, a citizen of the United States, residing at New Bedford, in the county of Bristol and State of Massachusetts, have invented a portable machine-wrench for turning nuts "wrench-tight" on the bolts of fish-jointed railway-bars, of which the following is a specification.

My invention consists in a perpendicular frame in cranks, gear-wheels, socket, socket-shaft, transverse rod, carrier, spiral springs, lever, and bolts.

Figure 1 is a perspective view of my invention applied to the fish-joint of a railroad-rail, as seen when operated on a railroad. Fig. 2 is a perspective view of my invention removed from the rail. Fig. 3 is a transverse view of the socket, socket-shaft, nut in the socket, fish-bolt, lever, reciprocating rod, carrier, annular groove, and spiral springs. Fig. 4 is a longitudinal section of socket, socket-shaft, and countersink. Fig. 5 is a transverse section of end of frame, showing the groove for edge of the web of the rail.

In Fig. 1, A is the frame for supporting the devices of the wrench. It stands perpendicular on the rail, as seen in operation.

B B B B are gear-wheels, which may be made of different diameters to produce desired power. They conduct the power of the operator from the cranks to the socket. The socket-wheel is cast with rib on the right-hand edge of its periphery, to prevent it from being forced out of position by action of the traveler.

C C are cranks for operating the wrench, and need no specification.

D is the socket for the fish-bolt nuts.

E is the socket-shaft. It is four-square where it passes through the gear-wheel B, and reciprocates transversely through it when the nut is turned off or on the fish-bolt. It is round where it revolves in the frame A, and has a countersunk hole, K, in its end at the bottom of the socket of sufficient depth to admit the end of the fish-bolt when the nut is turned on and the end of the bolt protrudes through the nut.

F is a foot-lever. It serves two purposes. It forces the fish-bolt nut, when placed in the socket, against the end of the fish-bolt by means of rod I, carrier J, and annular groove i, and clamps the frame A to the rail.

G is a spiral spring around rod I. This rod has a long mortise perpendicular through it, in which projection e of lever F passes and presses 55 against G when the foot of the operator rests on F.

J is the carrier, firmly secured to rod I, and rests in annular groove i.

H is a spiral spring. This spring forces the 60 socket off the nut after it has been turned on the bolt and the foot of the operator removed from lever F. The lower projection, g, of lever F is in shape of a cam, and when forced against the head of the fish-bolt j holds it in 65 position, and also clamps the frame A to the rail by projection h. When e presses against spiral spring G, it yields till projection g is brought firmly against the head of the bolt, while the tension of G continues and forces 70 the nut on the screw-thread of the fish-bolt, causing the screw "to take."

j, j are fish-bolt and nut. (See Fig. 3.)

d d are bolts which bind the frame together, and on which the gear-wheels revolve. 75

f is the end of frame A, and rests on the web 80 of the rail, which secures the machine in accurate position. This end may be made with groove m to fit the edge of the web of the rail for more permanently securing the wrench to the rail.

D is the socket; E, the socket-shaft; K, the countersink in the end of the shaft at the bottom of the socket, which is of sufficient diameter and depth to admit the end of fish-bolt j 85 when it protrudes through the nut and the nut is turned home.

By this invention any-sized nut, by change of socket, which will revolve above the web of the rail, may quickly be turned onto the fish-bolt with any desired tightness to hold them without any locking device. A round disk-nut which will revolve above the web of the rail may be turned on by driver instead of socket, if a channel be cut across the face of 95 the nut for insertion of the driver.

Other devices than gear-wheels shown for transferring the power of the operator from the crank-shaft to the socket may be used—bevel-gear wheels with perpendicular shaft or 100 endless chain, &c.

Other devices may be used for pressing the nut against the end of the fish-bolt and securing the wrench to the rail and fish-bolt in position

than the devices set forth. A screw for this purpose, or its equivalent, may be used.

The novelty and operation of my invention is so apparent that no further remark or specification need be made.

I claim—

1. Frame A A A, gear-wheels B B B B B, cranks C C, bolts d d d, end of frame f, with groove m, and projection h, with lever F, rod I, carrier J, socket D, with annular groove i, shaft E, with countersink K, and spiral springs G and H, as and for the purposes set forth and described.
2. Socket D, with its annular groove i, sock-

et-shaft E, with its countersink K, and mechanism for operating it through gear-wheel B, as and for the purposes set forth and described.

3. Lever F, with its projections e and g, and frame A, having projection h, and end f, with groove m, spiral springs G and H, rod I, carrier J, and socket D, with countersink K, and annular groove i, as and for the purposes set forth and described.

JNO. DAVIS.
